HEAT EXCHANGE ELEMENT

Nathan Kramer, Trenton, N. J., assignor to
 Kramer Trenton Company, Trenton, N. J., a
 corporation of New Jersey

Application March 19, 1943, Serial No. 479,688

1 Claim. (Cl. 257—262)

1 This invention relates to a heat exchange element and, more particularly, to a structural part including a tubular conduit and fins projecting laterally therefrom which is useful in radiators and the like.

An object of the invention is to provide a fin structure which is extremely simple and economical to manufacture.

Another object is to provide such a structure in which a plurality of fins are formed from a single piece of material and are connected by integral portions which serve to maintain the fins in fixed spaced relationship, to add rigidity to the structure, and to improve the operative effect of the radiator or the like.

Another object is to provide such a structure which is so formed and arranged that a plurality of fins may be simultaneously associated in operative contact and relationship with a tubular conduit in a simple and expeditious manner.

Another object is to provide such a structure which is adapted to be produced by a single pressing or stamping or dieing operation and to be formed in extended lengths which may be thereafter folded into a unitary plurality or group of fins suitable for association with a tubular conduit.

A further object is to provide certain improvements in the form, construction, and arrangement of the parts whereby the above named and other objects may be effectively attained and the general efficiency of the structure enhanced.

A practical embodiment of the invention is shown in the accompanying drawing in which

Fig. 1 represents a detail top plan view of an integral group of fins in operative association with a tubular conduit;

Fig. 2 represents a side elevation of the parts shown in Fig. 1;

Fig. 3 represents an end view thereof;

Fig. 4 represents a section of a strip of material which has been pressed, stamped or operated upon by a die to form the fins therein; and

Fig. 5 represents a perspective view of a unitary group of fins which has been folded from the strip of material shown in Fig. 4.

In this art, heat interchanging elements of radiators and the like commonly include a tubular conduit through which fluid is passed, and fins which are in contact with the exterior of the conduit and project laterally therefrom to act as radiating agents. Among other things, it is important that the fins be maintained in fixed predetermined spaced relationship with respect to each other in order that radiation may be uni-

2 form, or substantially so, along the conduit; and that the structure have sufficient rigidity or permanency to allow for bending the conduit intermediate groups of fins without disturbing their proper cooperative positioning or relationship; as well as to insure durability of the structure when in use. It is likewise important, from the point of view of production costs, that the fins may be economically and expeditiously manufactured and associated with the conduit. And again it is a matter of importance that the structure be such as to attain and maintain a very high degree of efficiency without undue increase in its bulk or weight.

15 Referring now to the embodiment of the invention set forth in the drawings, the reference numeral 1 denotes a tubular, and in this instance circular, conduit composed of suitable material that is preferably metallic and heat conducting such, for instance, as copper or brass.

The conduit 1 carries a plurality of fins 2, which are also preferably composed of a heat conducting metal such as copper or brass. The fins 2, which are preferably substantially rectangular in form, as illustrated in Fig. 3, are all alike and are interconnected by bridges or straps 3 which are formed integral with the fins and alternately connect the latter at opposite sides as shown in Figs. 1 and 5. Any desired number 25 of fins may be thus connected to form an integral group, which number will naturally vary according to the requirements of the product being manufactured.

Each fin is centrally pierced by a hole 4 of such 35 size as to fit the outer circumference of the conduit 1 while permitting the fins to be mounted on the conduit by sliding them thereon. This association of fins and conduit may be made rigid or fixed in several ways as, for instance,

40 by forming the hole in the fin slightly smaller than the conduit and then associating the parts after heating the fin and chilling the conduit; or by forming the hole in the fin slightly smaller than the conduit, then distorting the periphery

45 of the hole to permit association of the parts, and then restoring the distortion; or by expanding the conduit by hydraulic or mechanical means after the parts are associated; or by fusing the point of contact between the fin and conduit.

50 If either of the last two procedures is followed, the hole may be formed slightly larger than the conduit to facilitate association. Other suitable ways of assembling these parts will doubtless occur to operators skilled in this industry, and it may be emphasized that the interconnection

of the individual fins by the bridges or straps **3** tends to maintain a group of fins in fixed position on the conduit because the accidental or unintentional movement of any fin for even a very short distance along the conduit will at once cause its connection with the adjacent fin to cramp the latter angularly upon the conduit and thereby prevent further movement. This results primarily from the fact that the fins are interconnected at only one side as distinguished from a connection at both sides.

The conduit **1** may, of course, be formed in any well known or approved manner which it seems wholly superfluous here to exemplify. As to the fins, I prefer to form them from a strip or ribbon of sheet metal **5** which is first passed through suitable pressing devices, such as a pair of cutting rollers, which form the holes **4** and, intermediate the holes, form similar openings **6**, **6** connected by a slit **7**. Immediately after the said holes, openings and slits have been formed in the strip **5**, and preferably in a continuous operation, the strip may be fed between a pair of dies which fold the same into the zig-zag formation well represented in Fig. 5, and also shown in Fig. 1. In this dieing operation, portions of the strap adjacent the openings **6**, **6** are bent along the broken lines **8**, **8** so as to form wings **8**, **8** projecting laterally from and in the same plane with the fins **2**, which wings increase the radiating efficiency of the fins.

As such roller and die operations are well understood in the metal forming industry, it is regarded as unnecessary further to detail the same herein; and it should also be noted that any other suitable procedure for forming the fins may be followed.

The length of the strip **5** will be fixed in accordance with the predetermined number of fins to be formed as an integral unit, and such units may be located in spaced relationship on the conduit **1**, if desired, so as to permit the latter to be bent intermediate groups of fins in order

to change its course to conform with the design of the radiator or the like in which this heat exchange element is to be incorporated.

The bridges or straps **3** have not only the function hereinabove mentioned of preventing dislodgment of a group of fins from predetermined position on the conduit, but they also serve accurately to space the fins in order to promote uniformity of radiation, and materially increase the rigidity of the fin structure so as to obviate the necessity of employing separate elements to interconnect the fins, thereby leading to a substantial economy in both material and labor.

It will be understood that various changes may be resorted to in the form, construction, arrangement and material of this invention, and in the procedure followed in its manufacture, without departing from the spirit and scope of my invention; and hence I do not intend to be limited to the details herein shown and described except as they may be included in the claim.

What I claim is:

A heat exchange element including a plurality of integrally connected fins, each fin being connected at the top and bottom of one edge with the fin at one side thereof and at the top and bottom of another edge with the fin at the other side thereof, said fins having wings projecting between and beyond the points of interconnection and lying in the same planes as the fins.
